UNITED STATES PATENT OFFICE.

JAMES B. BEATTY, OF BROOKLYN, NEW YORK.

DESIGN FOR A FAN OR SIMILAR ARTICLE.

SPECIFICATION forming part of Design No. 18,499, dated August 7, 1888.

Application filed June 28, 1888. Serial No. 278,460. Term of patent 3½ years.

To all whom it may concern:

Be it known that I, JAMES B. BEATTY, a citizen of the United States, residing at the city of Brooklyn, county of Kings, and State of New York, have invented a new and original Design for a Fan or Similar Article, of which the following is a specification, reference being had to the accompanying illustration, forming part hereof.

10 The leading feature of my invention consists in a surface ornamentation, being the representation of a handkerchief of what is known as the "bandana" pattern, loosely thrown together, as shown, and having a plain field in the center of the picture, on which are 15 two faces or portraits.

A represents the handkerchief, having the various bandana figures B B upon it.

C is the plain space in the center, and D E 20 are the portraits or faces thereon and surrounded by overlapping circular portrait-spaces.

The effect produced is that of a bandana handkerchief loosely thrown together and hav-

ing the two portraits in overlapping circular portrait-spaces upon a plain card or ground lying upon it.

This design is particularly adapted by its character and configuration to be placed in the crown of a silk hat or upon a fan or similar article, and produces a very pleasing and attractive appearance.

Having thus described my invention, what I claim, and desire to secure by Letters Patent of the United States, is—

The design for a fan or similar article having a surface ornamentation consisting of the representation of a bandana handkerchief, A, loosely thrown together, and having a plain space, C, in the center thereof, with the overlapping circular portrait-spaces thereupon, containing the portraits D E, substantially as shown.

JAMES B. BEATTY.
